JOHN T. WOOLSEY, OF KANSAS CITY, KANSAS.

FLOAT-REGULATED SKIMMER.

1,199,851.

Specification of Letters Patent. Patented Oct. 3, 1916.

Application filed June 7, 1915. Serial No. 32,634.

To all whom it may concern:

Be it known that I, JOHN T. WOOLSEY, a citizen of the United States, residing at Kansas City, in the county of Wyandotte 5 and State of Kansas, have invented certain new and useful Improvements in Float-Regulated Skimmers, of which the following is a full, clear, and exact description, such as will enable others skilled in the art to 10 which it appertains to make and use the same.

The invention relates to skimmers for steam generators and seeks to provide a simple and efficient form of skimmer which may 15 be placed in the generator and the receiving orifice maintained always at an elevation near the surface of the water to receive a quantity of water together with any sediment or substance that will not evaporate 20 and conduct the same to a vessel where it may be precipitated, and from which the water may return to the generator by thermo-siphon.

It is not new to install skimmers in steam 25 generators to remove a portion of the foreign substance from the water by thermo-siphon and precipitation, but the desired results have not been fully realized owing to most devices of this kind being fixed rigidly 30 as to elevation and the construction not being such as to reach a sufficient amount of the surface of the water.

It is essential that the skimmer reach a considerable length of the generator so as to 35 draw from all parts of the surface, and that the weight be supported by the water so that the receiving orifices may be always submerged but near the surface where the sediment is first carried by the steam that is generated in the water in order that the sediment 40 may enter the skimmer before it has time to settle on the flues or shell of the generator.

The present invention seeks to provide an 45 improved automatically adjusting skimmer for steam generators, supported by a float, and means to prevent the float and skimmer from settling to too great a depth when the water is removed from the generator.

50 A further object of the invention is to distribute the receiving orifices throughout a considerable length of the generator and provide duplicate outlets near the center thereof, so that a greater surface may be 55 more freely drawn from and a greater quan-

70 tity of sediment removed from the generator.

A still further object is to so construct the skimmer that it is easily installed, and so that the parts cannot become misplaced by 60 the rising and falling of the skimmer due to the changes in elevation of the surface of the water in the generator.

With these and other objects in view the invention consists in the improved features 65 of construction, connections, combinations and arrangements of parts hereinafter described illustrated in the accompanying drawings and more particularly pointed out in the appended claims.

70 In the drawings:—Figure 1 is a view in elevation of a steam generator with a portion of the shell broken away to illustrate the location and attachment of the improved skimmer which is attached, the view also 75 representing the pipe connection to a fragment of a precipitator which is employed in connection with the skimmer but is no part of the present invention. Fig. 2 is an enlarged perspective view of the improved 80 skimmer. Fig. 3 is a still further enlarged fragmentary view of the hinge connection of the skimmer with the connecting nut broken away to show the pipe connection.

85 Connected to and extending downward within the generator 1 is a vertical pipe 2, the lower end of which is connected to the T 3, the latter being threaded on each end thereof, while abutting each end of the T is a horizontal pipe 4 with a collar 5 preferably integral therewith, the nut 7 being constructed to slide over the collar 5 and screw on the threaded end of the T and the nut being locked on the T by the tight fitting pin 8, the collar 5 loosely fitting the nut 90 allowing the pipe 4 to turn therein forming a hinge.

95 The skimming pipe 9 is connected to pipe 4 by T's 10, pipes 11 and elbows 12 and has 100 therein a number of openings on the top thereof adapted to admit water together with any sediment or substance that has risen with the steam to the surface of the water, the float 13 being preferably connected to the skimming pipe 9 by brazing as shown at 14, but any other suitable connection may be substituted therefor, the skimming pipe 9 being secured to the float 13 in 105 such a manner as to remain just below the surface of the water at all times.

110

Mounted on the top of the float 13 is a yoke 15 which is preferably brazed to the float but may be connected in any suitable manner, on the pipe 2 is fastened a clamp 5 strip 16 by means of the bolts 17, a hole being drilled in the ends thereof and a pin inserted to form a pivot bearing 18, the rod 19 connected thereto and inserted through the yoke 15 with the nut 20 and lock nut 21 to adjust the extreme lowering position of the float and skimming pipe.

A precipitator of the ordinary construction 22 is placed in any convenient place, the piping 23 connecting the vertical pipe 2 and 15 the receiving connection 24 of the precipitator to carry off the sediment or substance which rises to the surface in a steam generator. After the water is subjected to precipitation it is returned by thermo-siphon to the 20 bottom of the steam generator by the piping 25 which is connected to the discharging connection 26 of the precipitator and the receiving connection 27 of the generator.

It is understood that the water level in a 25 steam generator is always changing and is not usually maintained at any particular height within several inches, and that the hinge connections of the pipe 4 to the pipe 2 will allow the float to at all times hold the 30 skimming pipe 9 submerged to a certain distance.

In operation the pressure within the steam generator will force the water containing the sediment and foreign substance through the 35 pipes 2 and 23 to the precipitator 22 where the water is purified by the precipitation of the foreign substances owing to the slow

passage of the water through the precipitator and during this action the water becomes slightly cooled and returns by gravity or 40 thermo-siphon to the generator through the pipe 26, owing to the increased weight of the water in cooling.

What I claim as new, and desire to secure by Letters Patent, is:—

1. In a skimmer for steam generators, a steam generator, a discharge pipe leading downwardly and into the interior of said steam generator, horizontal pipe hinge connected to said discharge pipe, a perforated 50 skimming pipe secured to and connecting with said horizontal pipes, a cylindrical float secured to said skimming pipe, a rod engaging means secured to said float, a rod loosely mounted in said rod engaging means, 55 said rod hinged to said discharge pipe, and said rod provided with adjustable nuts to limit the downward movement of said skimmer.

2. In skimmers for steam generators, a 60 pipe leading into a generator, plural pipes hinged to said pipe, a perforated skimming pipe connected to said plural pipes, a cylindrical float integral with said pipe and extending throughout the length thereof and 65 adjustable means to limit the descension of said skimmer.

In testimony whereof I affix my signature in the presence of two witnesses.

JOHN T. WOOLSEY.
